(57) **CLAIM**

The ornamental design for an adjustable square ring shank assembly, as shown and described.

DESCRIPTION

FIG. 1 is a front elevational view of the adjustable square ring shank assembly showing our design in a retracted position.

FIG. 2 is a top side view thereof.

FIG. 3 is a bottom side view thereof.

FIG. 4 is a left side view thereof, which is identical to a right side view thereof.

FIG. 5 is a left interior section side view taken along line 5-5 of FIG. 1 with the shank of the adjustable square ring shank assembly in a retracted position, which is identical to a right interior sectional view thereof.

FIG. 6 is a front elevational view of the adjustable square ring shank assembly showing our new design in a deployed position; and,

FIG. 7 is a left interior sectional side view taken along line 7-7 of FIG. 6 with the shank of the adjustable square ring shank assembly in a deployed position, which is identical to a right interior sectional view thereof.

The broken line showing the gem setting is for illustrative purposes only and forms no part of the claimed design.
